TREATING PETROLEUM DISTILLATES

John A. Bolt, Chicago, Ill., assignor to Standard
Oil Company, Chicago, Ill., a corporation of
Indiana

Application March 9, 1944. Serial No. 525,664

6 Claims. (Cl. 196—29)

1

This invention relates to a process of removing mercaptans from petroleum distillates and particularly from "sour" gasoline and naphthas. More especially the invention relates to the extraction of mercaptans from gasoline with caustic solutions containing organic substances having the property of increasing the solubility of mercaptans in the caustic. These substances are generally known in the art as mercaptan solvents or "solutizers".

One object of the invention is to provide a process by which gasoline and naphthas may be readily treated by the caustic extraction process to produce a product which is sweet or substantially sweet to the doctor test and of satisfactory marketable character. Another object of the invention is to reduce the number of extraction stages by a combination extraction-oxidation process. Still another object of the invention is to reduce the cost of regenerating the caustic solution used in the extraction process and avoid losses of regeneration catalyst. Other objects of the invention will be apparent from the following description.

Many processes have been proposed for removing mercaptans from gasoline in order to improve the odor and the knocking characteristics. It has long been the practice to convert the mercaptans to disulfides by treatment with alkaline lead oxide, alkaline hypochlorite, and numerous other reagents to improve the odor. This process is generally known as sweetening. More recently it has been found that the disulfides have an undesirable effect on the knock rating of the gasoline and they particularly reduce the "lead susceptibility"—by which is meant that the response to treatment with lead tetraethyl is lessened by the presence of organic disulfides. Extraction of mercaptans with caustic solutions, generally caustic soda or caustic potash, has the advantage of actually removing the mercaptans from the gasoline instead of converting them to disulfides, and the extraction is considerably improved by the presence of phenols, organic acids, amines, alcohols, etc. Naphthenic acids, isobutyric acid, cresols and those phenols inherently present in gasoline, particularly cracked gasoline, are especially effective and the presence of these so-called solutizers is especially desirable in the extraction of the mercaptans of higher molecular weight.

When employing these caustic solutions it has been the practice to regenerate them either by steaming out the mercaptans or by oxidizing the mercaptans to disulfides by means of atmospheric

2

oxygen. This oxidation of mercaptans may be carried out either in the presence of the gasoline or in a separate step. In the former case the disulfides which result dissolve in the gasoline while in the latter case they may be separated and discarded from the process and thus prevented from contaminating the treated gasoline. The oxidation may be accelerated by various catalysts, particularly the polyphenols, tannic acid, hydroquinone, etc. Where an oxidation catalyst is used it is desirable to control the air-blowing or oxidation of the caustic solution to avoid oxidizing the catalyst itself to a point where its effectiveness is destroyed.

In practice, it has been found necessary in the regeneration of the caustic mercaptan solution to halt the oxidation short of complete mercaptan removal in order to prevent destruction of the regeneration catalyst. As a result appreciable amounts of mercaptans are left in the extracted gasoline owing to the inability of the partially regenerated solution to remove all the mercaptans. Furthermore, in order to obtain an extracted gasoline of low mercaptan content, an extremely efficient extraction process is required.

According to my invention, I control the air regeneration of the caustic solution so that the regenerated caustic solution retains a small but essential amount of mercaptans sufficient to prevent destruction of the regeneration catalyst. I then contact the gasoline previously extracted to a low mercaptan content, for example to less than ten milligrams of mercaptan sulfur per hundred milliliters with the regenerated caustic solution, and introduce sufficient air in the presence of the gasoline and regenerated caustic solution to oxidize the remaining mercaptans in the gasoline at the point of air introduction in order to render the gasoline sweet or substantially sweet to the doctor test. In carrying out the process in the above manner, the heavier mercaptans which are the most difficult to extract and yet most readily oxidized are converted to disulfides in the presence of the regenerated solution without materially reducing its mercaptan content. The caustic solution is then employed in the usual way to extract the gasoline after which it is recycled to the regeneration step of the process.

Referring to the drawing, gasoline, either straight-run or cracked gasoline or a naphtha fraction suitable for gasoline blending, is introduced to the process by line 10 leading to mercaptan extractor 11 wherein it flows upwardly countercurrent to a stream of caustic solution introduced by line 12. Extractor 11 is provided

with suitable contacting elements, baffle plates, ceramic packing, etc., or the extractor 11 may be substituted by a series of extraction stages arranged for countercurrent operation in the manner well known in the art. If the feed stock contains a considerable amount of phenolic material or hydrogen sulfide, it is desirable to extract the hydrogen sulfide and part of the phenolic material by a preliminary caustic washing treatment in pretreater 13 supplied by a caustic solution thru line 14 which may be withdrawn at intervals or continuously by line 15. The amount of pretreating may be controlled by valves in lines 16 and 17. If the feed stock has been properly stabilized, i. e. freed of propane, then it will be substantially free of hydrogen sulfide also and it will only be necessary to remove from it phenols and naphthenic acids which may be present in sufficient quantity to interfere with the subsequent operation of the caustic extractor where phenols and acids tend to accumulate by solution in the caustic.

The mercaptan extractor 11 is suitably supplied with a caustic solution containing about 10 to 30% of the anhydrous caustic, generally caustic soda or caustic potash along with 5 to 30% of cresols, xylenols or other phenols, isobutyric acid, naphthenic acids or other suitable solvent for mercaptans. In case of cracked stocks and gasoline from certain crudes, there is usually enough phenols present to supply solutizer needed in the caustic solution. These cresols, xylenols, etc., build up in the caustic owing to their weakly acidic nature. In addition to the solutizer, the caustic solution contains a catalyst for accelerating regeneration by oxidation. Thus for example, about 0.1 to 2% of a polyphenol such as catechol, hydroquinone or tannic acid (tannin) may be used. Tanning is particularly desirable because of its relatively low cost.

As the gasoline flows upwardly thru extractor 11 the mercaptans are selectively dissolved in the caustic solution. The temperature is commonly maintained at ordinary temperature although temperatures of 40 to 100° F. may be employed satisfactorily. Lower temperatures are favorable to extraction of mercaptans.

The caustic solution with dissolved mercaptans is withdrawn by line 18 from the base of the extractor and flows thru heater 19 to caustic regenerator 20 which is suitably a packed or baffled tower. Alternatively an agitated pressure vessel suitable for pressures of 100 to 500 pounds per square inch may be used. Sufficient heat is introduced at 19 to provide a temperature in the regenerator of about 100 to 150° F., e. g. 130° F., although under some conditions, using especially active regeneration catalysts, the temperature in the regenerator may be the same as in the extractor 11. Air is injected into the tower 20 by line 21 and passes out by line 22 and as indicated above, the air may be introduced under pressure. The amount of air introduced is controlled by valve 23 to prevent excessive oxidation which would destroy the regeneration catalyst, for example tannin. The reaction in regenerator 20 consists essentially in converting mercaptans to organic disulfides which are oily substances insoluble in the caustic solution. The following equation in which "R" is a hydrocarbon radical represents the reaction:

From the regenerator 20 the caustic solution

flows into separator 24 from which the disulfides are withdrawn continuously or periodically by line 25. The partially regenerated caustic solution should contain about 100 to 400 mgs. per 100 ml. of residual mercaptan sulfur. If the mercaptan sulfur is reduced to an amount appreciably lower than this, a substantial loss in regeneration catalyst will result. If the mercaptan sulfur of the partially regenerated caustic is allowed to appreciably exceed 400 mgs. per 100 ml., the subsequent sweetening operation will not be satisfactory and an excessive amount of disulfide may be introduced into the gasoline product. It is preferred to control the regeneration in 20 to produce a partially regenerated caustic solution having a residual mercaptan sulfur content of 200 to 300 mgs. per 100 ml.

From separator 24 the regenerated caustic solution goes by line 12 and cooler 12a back to the top of the mercaptan extractor 11. In the upper section of the mercaptan extractor the caustic solution comes in contact with the gasoline from which most of the mercaptans have been extracted. A stream of air is introduced by line 26 in the upper section of the mercaptan extractor just sufficient to convert the mercaptans remaining in the gasoline to disulfides without appreciably lowering the mercaptan content of the caustic. When operating with a multi-stage extraction unit the required amount of air may be introduced ahead of the last extraction stage. It is desirable to reduce the mercaptan sulfur content of the gasoline in extractor 11 to less than 10 mgs. per 100 ml. and preferably to less than 5 mgs. per 100 ml. when the gasoline reaches the point where air is introduced into the extraction system. On conversion of these residual mercaptans to disulfides by air oxidation in contact with the caustic solution, a sweet or substantially sweet gasoline is readily obtained.

The presence of the gasoline serves to speed the reaction between air and mercaptans dissolved in the caustic-solutizer solution, possibly shifting the equilibrium in the direction of disulfide formation and also perhaps by its action in supplying dissolved oxygen to the caustic solution. There are indications that the oxidation reaction may proceed largely in the oil phase. If the caustic solution supplied to the extractor by line 12 has been heated it is usually desirable to cool it before passing it to the lower section of the extractor in order to obtain a more favorable equilibrium for mercaptan extraction. This may be accomplished by trapping out the caustic solution on trapout plate 27, passing it by line 28 to cooler 29 and thence back to the extractor by line 30.

Gasoline is withdrawn from the top of extractor 11 by line 31 leading to water wash tower 32 where any entrained caustic solution is removed by a water spray introduced by line 33, the waste water being withdrawn by line 34. Any excess of caustic solution entrained in the treated gasoline may be coalesced by passing it thru metal wool or other porous material, then collected and returned to the system, if desired, before the final washing step. The finished gasoline is withdrawn to storage by line 35 and undissolved air, principally nitrogen, which was introduced by line 26 is vented from the wash tower by line 36.

Fresh caustic for the process may be supplied from tank 37 and line 38. Additional regeneration catalyst, for example a solution of tannin,

may be supplied by line 39 and additional cresol or other solutizer may be supplied by line 40 if necessary.

In the operation of my process, it appears that the heavy mercaptans are selectively oxidized and removed in the regenerator so that the caustic solution returned to the gasoline treater contains mainly mercaptans of low molecular weight which are resistant to oxidation but which are preferentially soluble in the caustic. Consequently they are not redissolved in the gasoline nor are they removed readily by the air oxidation in extractor 11; thus they serve to protect the regeneration catalyst without interfering with the removal of mercaptans from the gasoline. Where the gasoline stock treated is deficient in mercaptans of low molecular weight, I may add them in small amount for the purpose just described. Thus I may add, continuously or intermittently, methyl, ethyl, or, less desirably, propyl mercaptan to the caustic solution flowing to the regenerator or, preferably by line 41 and line 12 leading to the treater. Alternatively, I may regenerate caustic in two stages, adding the light mercaptans to the second stage and oxidizing therein to convert substantially all the heavy mercaptans to disulfides which are removed before recycling to the gasoline treater. Where stage regeneration is practiced, the light mercaptans can be added to the last stage. Also, the stream of partially regenerated caustic solution can be split and a portion only sent to the sweetening zone with air blowing, the other portion being added to a lower stage of the fractionator 11 by line 42 shown dotted.

Having thus described my process what I claim is:

1. In the process of sweetening a sour petroleum distillate wherein mercaptans are extracted from said distillate by contacting in an extraction zone with a caustic alkali solution containing a solutizer and a regeneration catalyst comprising a phenolic hydroxy compound, separating caustic solution from distillate and partially regenerating the caustic solution by oxidation with an oxygen-containing gas, limiting the oxidation of said caustic solution to prevent destruction of said regeneration catalyst by allowing a substantial amount of residual mercaptans to remain unoxidized in said caustic solution, separating organic disulfides from partially regenerated caustic solution, and recycling the partially regenerated caustic solution from the regeneration zone to said extraction zone, the improvement comprising intimately contacting said partially regenerated caustic solution in a sweetening zone with distillate from said extraction zone, injecting air into said sweetening zone in an amount sufficient to complete the oxidation of mercaptans in the presence of said distillate and produce a substantially sweet distillate product, then conducting the caustic solution from said sweetening zone to said extraction zone.

2. The process of claim 1 wherein said organic regeneration catalyst is a polyphenol.

3. The process of claim 1 wherein said caustic regenerator is operated at a temperature of about 100 to 150° F. and the caustic solution is cooled before returning to said extraction zone.

4. The process of removing mercaptans from sour gasoline to provide a gasoline substantially sweet to the doctor test which comprises extracting a major proportion of the mercaptans from said gasoline in an extraction stage, oxidizing remaining mercaptans to disulfides in an oxidation stage in the presence of a phenolic mercaptan oxidation catalyst, conducting a strong caustic alkali solution containing a solutizer thru said oxidizing stage and then thru said extraction stage in series, countercurrent to the flow of gasoline, separating said caustic solution from gasoline in said extraction stage, regenerating said caustic solution by oxidizing a major proportion of dissolved mercaptans to disulfides insoluble in said caustic solution, separating disulfides from said caustic solution, returning said solution to said oxidation stage and supplying an oxygen-containing gas to said oxidation stage to complete the conversion of residual mercaptans contained in said caustic solution and said gasoline.

5. The process of claim 4 wherein said solutizer is a mixture of phenolic substances present in small amounts in the gasoline being treated and which accumulate in the caustic solution recycled in the process.

6. In the process of removing mercaptans from a sour petroleum distillate wherein said distillate is extracted countercurrently in an extraction stage with a caustic alkali solution containing about 5 to 30% of a solutizer having the effect of increasing the solubility of mercaptans in said caustic solution sufficiently to extract substantially all of the light mercaptans and a major part of the heavy mercaptans contained in said sour distillate leaving less than about 10 mg. mercaptan sulfur per 100 ml. of distillate, wherein the said caustic alkali solution containing dissolved mercaptans is separated from the gasoline and regenerated by oxidation with an oxygen-containing gas at about 100 to 150° F. in the presence of about 0.1 to 2% of a regeneration catalyst comprising a polyphenol soluble in said caustic solution, substantially all the heavy mercaptans being converted to organic disulfides by the regeneration reaction, leaving about 200 to 300 mg. of light mercaptan sulfur per 100 ml. unoxidized in said caustic solution to protect said regeneration catalyst from oxidation, and wherein said organic disulfides are separated from said regenerated caustic solution and the said solution is recycled for treating additional distillate, the improvement comprising intimately contacting with an oxygen-containing gas in an oxidation stage, said regenerated caustic solution and extracted distillate from said extraction stage thereby selectively converting the residual heavy mercaptans in said extracted distillate to disulfides substantially without oxidizing said light mercaptans remaining in said regenerated caustic solution, and thereafter conducting the caustic solution from said oxidation stage to said extraction stage, where it is employed for the extraction of further quantities of sour petroleum distillate.

JOHN A. BOLT.
